(57) **CLAIM**

The ornamental design for an display screen or portion thereof with an animated graphical user interface showing an electronic ATM, as shown and described.

DESCRIPTION

FIG. 1 is a front view of a display screen or portion thereof with an animated graphical user interface showing an electronic ATM showing a first image in a sequence of our new design; and,

FIG. 2 is a second image thereof.

The subject matter in this patent includes a process or period in which an image changes into another image. This process or period forms no part of the claimed design.

The dot dash dot broken lines represent a Display Screen and form no part of the claim. The dash-dash-dash broken lines represent stitching and are part of the claim.
